UNITED STATES PATENT OFFICE

CLAUDE H. BRIGHT, JR., OF MEMPHIS, TENNESSEE

INK PAD WITH REVERSIBLE PLATE

Application filed March 20, 1930. Serial No. 437,477.

This invention relates to ink pads, particularly those of the reservoir type and it has for its principal object the provision of means interposed between the reservoir and the stamp pad for controlling the amount of ink transmitted from said reservoir to said stamp pad so that the latter can never become objectionably saturated.

Another object of the invention is to provide means for transferring ink from the reservoir to the stamp pad involving two successive functions, respectively, the absorption of a limited amount of ink from the reservoir or other supply source, and the transmitting and distributing of the ink from the absorbing means to the stamp pad by capillary attraction.

Other objects of the invention will appear as the following description of a preferred and exemplary embodiment thereof proceeds.

In the drawings which illustrate the accompanying specification, and in which the same characters of reference are used throughout the several figures to denote identical parts:

Figure 1 is a perspective view of an ink pad constructed to follow the principles of the invention;

Figure 2 is a longitudinal vertical section taken along the line 2-2 of Figure 1;

Figure 3 is a cross section taken along the line 3-3 of Figure 2;

Figure 4 is a perspective view, parts being broken away and the stamp pad being removed;

Figure 5 is a perspective view of the reservoir portion of the ink pad; and

Figure 6 is a cross section through the transfer plate.

Referring now in detail to the several figures, a casing 1 is provided in which rests a frame 2, the latter cooperating with the interior bottom wall of said casing to form a reservoir for ink. The top wall 3 of the frame 2 is preferably provided with a depressed portion 4 slotted as indicated at 5 in Figure 2 to permit the passage of a wick 6, preferably doubled, the folded portion of which rests upon the bottom of the reservoir

while the ends are spread in opposite directions, in the depression 4, the thickness of the wick being such as to cause it to extend slightly above the top of said depression so that it must necessarily make intimate contact with the transfer plate 7.

It will be noted in Figure 2 that the bottom of the casing slopes toward one end and that the folded portion of the wick extends to the lowest point of said casing so that the last drop of ink in the reservoir may be utilized. It is to be understood that while this represents an ideal construction, the invention in its broader aspect is not limited to the details of construction as shown.

The transfer plate 7 is removable and reversible, being preferably provided with a handle 8 by means of which the reversing operation may be conveniently carried out. The transfer plate is shown as resting upon the edges of a gasket 9 and having its central portion in contact with the ends of the wick 6. The transfer plate is preferably of metal having fixed to its opposite sides absorptive pads 10 and 11, preferably of absorptive textile fabric. It is the intention of the invention that the pads on the opposite sides of the transfer plate 7 shall be entirely separated from one another, and if the pads are constituted by a continuous sheet of fabric extending around the ends of the plate and covering both sides as is shown in Figure 6, then the end portions are preferably treated with some substance, as indicated at 12, or otherwise constructed so as to render said end portions non-absorptive with the object in view of preventing ink applied to one side of said transfer plate from creeping around to the other side.

Seated upon the transfer plate 7 is the stamp pad 13. This may be of any desired construction, but preferably consists of a metallic sheet bent so as to form upper and lower parallel flat surfaces 14 and 15, respectively, and a connecting end surface 16, said parallel surfaces and said end surface being covered by a continuous pad 17 preferably of absorptive textile fabric.

The free ends of the metallic sheet 14 may be secured in any suitable manner to a rigid

bar 18 and provided with a suitable handle 19 by means of which the entire stamp pad may be removed or reversed when desired. The upper and lower layers of the textile fabric 17 are in free absorptive communication by way of the portion of fabric which covers the end 16 of the stamp pad so that ink transferred to the lower layer of said textile fabric will creep by capillary attraction around the end 16 of the stamp pad, and will be uniformly distributed over the upper or stamp engaging surface thereof.

In operation, it being assumed that the transfer plate has lain upon the wick 6 long enough to have its lower pad 11 saturated with ink, it is then reversed so as to place the saturated pad upper-most and place the fresh dry pad in contact with the wick. The stamp pad now having its lower surface in intimate contact with the saturated pad of the transfer plate receives ink therefrom, which ink traverses the absorptive fabric 17 by capillary attraction as has been explained, uniformly moistening the entire upper surface of the stamp pad. It is obvious that no more ink can be supplied to the stamp pad than that contained in the upper pad of the transfer plate so that there is no risk whatsoever of the stamp pad becoming over-

30 saturated with ink from the reservoir. At a convenient time, and preferably before the top surface of the stamp pad becomes exhausted, the stamp pad is lifted out and the transfer plate merely reversed 35 whereupon the stamp pad is replaced. A new, but limited supply of ink which, in the meantime has been absorbed by the reservoir, is now placed uppermost in contact with the lower surface of the stamp pad so that the latter is now uniformly replenished.

Reversal of the transfer plate from time to time is all that is necessary in order to keep the stamp pad replenished and there is no risk of the stamp pad becoming over-

45 saturated. If, by chance the stamp pad is used without reversing the transfer plate, until the top surface thereof becomes substantially dry and inoperative, immediate relief may be had by reversing the stamp pad, bringing uppermost that surface which has been in contact with the transfer plate and which, not having been exposed to the evaporative effect of the atmosphere, will be found fit for immediate use. At the same time the reversal of the stamp pad is made, the transfer plate should also be reversed so that a new supply of ink begins to percolate the stamp pad so that the moist condition of the latter will 55 be fully restored before the working surface thereof becomes entirely depleted.

The casing 1 is preferably provided with a lid 20 adapted to be kept closed when the pad is not in use for excluding dust and minimizing evaporation. This feature is of course

well known and no claim to invention is based thereupon.

While I have in the preferred embodiment of the invention as illustrated, provided a reservoir having ink and a wick for feeding it to the transfer plate, the practice of the invention does not necessarily require the provision of a reservoir, for the mere wetted wick with which the under side of the transfer plate makes contact, is the full equivalent of a reservoir, although it requires a more frequent renewal of the ink supply.

It is to be understood that the invention is not limited to the specific details of construction as shown, which are merely by way of example and not to be considered as limitative in their bearing upon the scope of the invention as claimed.

What I claim as my invention is:

1. In an ink pad, an ink supply and a stamp pad, a transfer plate between said ink supply and said stamp pad having an absorptive surface adapted to absorb ink from said ink supply, said plate being manipulable to bring said surface alternatively into absorptive relation to said ink supply and stamp pad.

2. In an ink pad, an ink supply and a stamp pad, a transfer plate between said ink supply and said stamp pad having an absorptive surface adapted to absorb ink from said ink supply, said transfer plate being reversible to bring said surface into absorptive relation to said stamp pad.

3. In an ink pad, an ink supply and a stamp pad, a transfer plate between said ink supply and stamp pad having transfer pads on its opposite faces formed by a continuous sheet of absorptive material adapted to absorb said ink from said ink supply, means forming an absorption barrier at the ends of said absorptive sheet segregating the opposite surfaces of the sheet, said plate being reversible to bring said transfer pads into absorptive relation to said stamp pads.

4. In an ink pad, an ink supply and a stamp pad, the latter having upper and lower faces formed of a continuous absorptive sheet of material, and reversible means intermediate said ink supply and stamp pad for alternately receiving a limited amount of ink from said ink supply and transferring it to said stamp pad.

5. An ink pad as claimed in claim 4, the stamp pad being reversible.

6. In an ink pad, an ink supply and a stamp pad, a transfer plate between said supply and stamp pad having independent absorptive upper and lower pads adapted to absorb ink from said ink supply, said transfer plate being reversible to bring said transfer pads alternately into absorptive relation to said stamp pad, the latter having upper and lower surfaces formed of a continuous sheet of absorptive material.

7. An ink pad as claimed in claim 6, the stamp pad being reversible.

8. In an ink pad, means forming a reservoir, a wick extending within said reservoir and having a portion thereof on the exterior 5 of said reservoir, a transfer plate having independent absorptive pads on its opposite surfaces positioned with one of said transfer pads against said wick, and a stamp pad positioned upon said transfer plate having 10 continuous upper and lower surfaces, the lower one of which contacts with the upper transfer pad, said transfer plate being reversible.

9. An ink pad as claimed in claim 8, the stamp pad being also reversible.

15 10. In an ink pad, an ink supply, a transfer plate, and a stamp pad, superposed in the order named so that the transfer plate contacts with the ink supply and the stamp pad, said transfer plate and stamp pad being two 20 sided and reversible, the two sides of the stamp pad being absorptively connected, and the two sides of the transfer plate being segregated by a non-absorptive barrier.

In testimony whereof I affix my signature.
